United States Patent

Des. 237,420
Patented Oct. 28, 1975

237,420

BATTERY CARRIER

Ronald Slomkowski, Toledo, Ohio, assignor to
Eltra Corporation, Toledo, Ohio

Filed Nov. 21, 1973, Ser. No. 418,014

Term of patent 14 years

Int. Cl. D3—02

U.S. CL. D87—1 R

Fig. 1

Fig. 2

Fig. 3

FIG. 1 is a side elevational view of a battery carrier showing my new design, the opposite side being identical thereto;

FIG. 2 is an end elevational view thereof, the opposite end being identical thereto and the broken line showing of a battery being for purposes of illustration only; and

FIG. 3 is a top plan view of the battery carrier.

I claim:

The ornamental design for a battery carrier, as shown and described.
